UNITED STATES PATENT OFFICE.

WALTER H. WANGELIN, OF BELLEVILLE, ILLINOIS.

SAND-MOLD-CHARGING APPARATUS.

No. 899,640.

Specification of Letters Patent.

Patented Sept. 29, 1908.

Application filed July 20, 1907. Serial No. 384,719.

To all whom it may concern:

Be it known that I, WALTER H. WANGELIN, a citizen of the United States of America, residing at the city of Belleville, in the 5 county of St. Clair and State of Illinois, have invented certain new and useful Improvements in Sand-Mold-Charging Apparatus, of which the following is a full, clear, and exact description, reference being had to the accompanying drawings, forming part of this 10 specification.

My invention relates to an apparatus for charging sand into flasks in which molding operations are performed and it has for its 15 object the production of an apparatus of this character of simple, inexpensive and efficient nature.

Figure I is a side elevation of my mold charging apparatus. Fig. II is an enlarged 20 vertical longitudinal section taken through the apparatus. Fig. III is an enlarged vertical transverse section taken on line III—III, Fig. I. Fig. IV is a vertical section taken on line IV—IV, Fig. II. Fig. V is an elevation of the vibrator that receives the 25 sweep of the apparatus.

In the accompanying drawings, 1 designates a hopper that is adapted to receive the sand to be delivered to a molding flask A, 30 illustrated in Fig. I. In this hopper is a feeder by which the sand, whether in a dry or wet condition, is conveyed in a downward direction to the bottom of the hopper. The feeder, for which no invention *per se* is herein 35 claimed, comprises a frame 2 unsupported at its upper end and rockably mounted at its lower end upon a shaft 3, and an endless carrier 4 that is operable upon toothed wheels 5 fixed to the shaft 3 and toothed 40 wheels 6 fixed to a shaft 7 mounted in the upper end of the frame 2.

Beneath the hopper 1 is a receiver 8 and in this receiver is a winged drum 9 supported by a rotatable shaft 10. Extending from 45 the bottom of the receiver 8 is a chute or runway 11.

12 designates a charging barrel that has communication with the receiver 8 through the medium of the chute 11 and which is 50 provided with an outlet spout 13 located at its lower side and beneath which the flask A is adapted to be placed, as seen in Fig. I. 14 is a shaft which extends transversely through the barrel 12. 55 15 is a sweep arm sleeve that is secured to the shaft 14 so that it will be rotated by said

shaft within the charging barrel and which is provided with one or more sweep arms 16 that carry a sweep plate 17. The sweep, composed of the members just referred to is 60 adapted to be rotated by the shaft 14 in the direction indicated by the arrow, Fig. II, so that its plate will oppose the feed of, and gather sand as it enters into the charging barrel through the chute 11 and carries such 65 sand in an upward direction and then throws it in a downward direction with force through the spout 13 of the charging barrel and into the flask placed beneath said spout. By this action of the sweep, the sand is delivered 70 into the flask in a manner to efficiently pack it therein in the process of forming a mold in the flask.

18 designates a vibrator that is adapted to be engaged by the sweep during its operation in the charging barrel 12. This vibrator is pivotally supported by a rod 19 and has an arm 20 located exterior of the barrel and a finger 21 located interior of the barrel.

22 is a retracting spring that connects the 80 arm of the vibrator to the charging barrel and serves to normally hold the inner arm of the vibrator in the path of travel of the sweep plate 17.

In the operation of my apparatus, the 85 sand to be packed in a flask such as A located beneath the spout of the charging barrel 12, is fed from the hopper 1 into the receiver 8 by the carrier 4 and from said receiver to the chute 11 and charging barrel by the winged 90 drum 9. At the same time rotation is imparted to the sweep in the charging barrel so that it will move in the opposite direction to the feed indicated by the arrow, Fig. II. The parts just described are driven by suitable mechanism, such as illustrated in Fig. I or any other desirable form of mechanism. As 95 the sweep is rotated in the charging barrel, it first carries the sand in an upward direction against the feed and then, after reaching a position at the top of the barrel and beginning its downward movement, the sweep throws the sand through the spout 13 of said barrel forcibly, with the result of causing the sand to enter the flask placed beneath said 100 spout to be packed solidly therein, as will be readily understood. Each time that the sweep reaches the vibrator 18 its plate 17 strikes against the finger 21 of the vibrator, thereby imparting a shock to said sweep with 105 the result of jarring particles of sand from the plate that may have adhered thereto, so

that the plate will be in a clean condition to pick up the next charge of sand in its next circular movement. The vibrator being spring controlled, yields to the pressure of the sweep thereagainst immediately after it has served its function of jarring the sweep, and the sweep plate may therefore pass the vibrator which will be returned to its normal position by the spring 22, in order that the sweep plate may engage it upon its next movement thereto.

I claim:

1. In an apparatus of the character described, the combination of a charging barrel having an inlet and an outlet, said outlet being substantially off center, and a sweep rotatably mounted in said barrel; said barrel being entirely closed aside from its inlet and outlet to provide for material being forcibly driven from the barrel through its outlet when said sweep is rotated, substantially as set forth.
2. In an apparatus of the character described, the combination of a charging barrel having an outlet, means for delivering the material into said barrel, a sweep rotatably mounted in said barrel, and means for rotating said sweep, against the feed, and throwing it through the outlet; substantially as set forth.
3. In an apparatus of the character described, the combination of a charging barrel having an outlet, means for delivering material into said barrel, a shaft rotatably mounted in said barrel, and a sweep carried by said shaft in the opposite direction to the feed; said sweep gathering the material and throwing it through the outlet, substantially as set forth.
4. In an apparatus of the character de-

scribed, the combination of a charging barrel having an outlet, a chute leading to said barrel, means for feeding material through said chute to said barrel and a revoluble sweep operable in said barrel and which is adapted to gather the material as it enters said barrel against the feed and discharge it through said outlet, substantially as set forth.

5. In an apparatus of the character described, the combination of a hopper, a receiver having communication with said hopper, a feeder in said hopper a feeder in said receiver, a chute leading from said receiver, a barrel with which said chute communicates and which is provided with an outlet spout, and a sweep revolvably mounted in said barrel to operate in the opposite direction to the feed; said sweep gathering the material and throwing it through the outlet, substantially as set forth.

6. In an apparatus of the character described, the combination of a charging barrel having an outlet, means for delivering material into said barrel, a sweep operable in said barrel, means for rotating said sweep, and a vibrator arranged in the path of movement of said sweep, substantially as set forth.

7. In an apparatus of the character described, the combination of a charging barrel having an outlet, means for delivering material into said barrel, a sweep operable in said barrel, means for rotating said sweep, and a spring controlled vibrator arranged in the path of movement of said sweep, substantially as set forth.

WALTER H. WANGELIN.

In the presence of—

LILY ROST,
L. C. TAAKE.
